UNITED STATES PATENT OFFICE

2,006,462

MINIATURE BUILDING CONSTRUCTION

William Kupper, Lakewood, Ohio

Application March 12, 1934, Serial No. 715,092

2 Claims. (Cl. 46—35)

This invention, as indicated, relates to a miniature building construction. More particularly, it comprises a series of building elements which may be interlockingly connected with each other 5 so as to produce substantially in miniature form various types of buildings which very closely approximate buildings which may be constructed for occupancy of full size. The construction therefore can be used not only for toy purposes, but 10 for demonstration and experimental purposes by adults as well as children, who seek to visualize the prospective building they have in view actually constructing preliminary to finally determining upon various floor plans and arrangements.

15 The principal object of the present invention is to provide a miniature building construction having units which may be interlockingly engaged and present various artistic and useful forms of building construction.

20 Another object of the invention is to provide a miniature building construction which may be used by children for amusement purposes and which will be free from the disadvantage which follows the use of ordinary toy building blocks 25 in that the latter are subject to accidental displacement whereas with the construction herein the parts are so interlocked that they may be handled freely without disturbing the relation of the units to each other.

30 Another object of the invention is to provide a series of building units of miniature type which will permit the erection of structures simulating full size structures and which will have a considerable variety of interchangeable units so as to 35 permit alcoves, bay windows, and various types of roof construction to be employed.

Another object of the invention is to provide window units in the form of thin metal elements 40 adapted to be interlockingly engaged with the building units and also to provide different types and character of roof sections which may be selectively applied to the various structures undertaken and suitably cover such structures after they have been completed.

45 Another object of the invention is to provide units of such shapes and lengths as will permit angular units to be used in combination with regular units so as to reduce the total number of units required to introduce special features of 50 construction such as alcoves and bay windows.

Other and further objects of the invention will appear in the course of the following description.

To the accomplishment of the foregoing and related ends, said invention, then, consists of the 55 means hereinafter fully described and particu-

larly pointed out in the claims, the annexed drawings and the following description setting forth in detail certain structures embodying the invention, such disclosed means constituting, however, but several of various forms in which the principle of the invention may be used.

In said annexed drawings:

Figure 1 is a front elevation of a miniature building constructed in accordance with the invention;

Figure 2 is a side elevation of the structure shown in Figure 1;

Figure 3 is a front elevation of another type of miniature building embodying the principles of the invention;

Figure 4 is a side elevation of the structure shown in Figure 3;

Figure 5 is a front elevation of still another type of miniature building embodying the principles of the invention;

Figure 6 is a side elevation of the structure shown in Figure 5;

Figure 7 is a fragmentary perspective view showing the constructional elements employed in erecting the various buildings;

Figure 8 is a top plan view of a foundation board for a miniature building;

Figure 9 is a perspective view showing a window frame and method of positioning the same;

Figure 10 is a perspective view showing a modified form of window frame;

Figure 11 is a perspective view showing one form of door frame;

Figures 12 to 17 inclusive are top plan views of building units for forming the structures illustrated in Figures 1 to 6 inclusive;

Figures 18 to 23 inclusive are side elevations of the units shown in said respective plan views;

Figures 24 and 25 are fragmentary plan views showing combinations of regular and special 40 length building units to form an enlarged corner structure and an alcove respectively;

Figure 26 is a perspective view showing an elongated horizontal strip; and

Figure 27 is a perspective view showing one of 45 the interlocking bars.

As will more clearly appear from Figures 12 to 27 of the drawings, the units used for the construction are of several different forms, Figures 12 and 18 illustrating a double unit 1 of rectangular shape having two apertures 2 for engagement by interlocking bars, and Figures 13 and 19 illustrating a single unit 3 of rectangular shape having an aperture 4 for engagement by a single interlocking bar. Figures 14 and 20 illustrate a 50 55 60 65 70 75 80 85 90 95

unit 5 of rectangular shape at one end and beveled at the opposite end, and Figures 15 and 21 show a unit 6 beveled at each end, each of the last-mentioned units having apertures 7, 8, respectively, for two interlocking bars.

Figures 16 and 22 show an extra length unit 11 having apertures 12 for interlocking bars, and having beveled ends provided with parallel long beveled faces 13 at opposite ends of the unit, 10 and with parallel short beveled faces 14 at opposite ends of the unit, providing a block adapted to be used in constructing an alcove in the manner shown in Figure 25, wherein the elongated blocks 15 are set at an angle of 45 degrees to the regular blocks with a portion thereof projecting freely beyond the side walls of the regular units and meeting one or more regular units outwardly of the normal position of such units without lost space because of the offset relation of such beveled blocks. Thus, as is shown in Figure 25, the unit 1A is of the same length as the unit 1B, and fits between the units 11A and 11B, even though they are of greater length than the other units. In this manner an alcove or like structure can be 25 built by using standard units with the extra length beveled end units just described.

The block unit 15 shown in Figures 17 and 23 is of extra length and is provided with three rod-receiving apertures disposed so that when said 30 block is set angularly to the regular blocks, two of such apertures 16 at the ends of the block will be in alignment with the apertures in the regular blocks, as is shown in Figure 24. Said blocks are also provided with an intermediate aperture 17 35 disposed centrally of the elongated blocks. In place of such elongated blocks being rectangular, as seen in plan view, the outer corners 18, 19, of said units are beveled, thus providing for a bay window effect at the corners of the building, 40 should the same be desired. This is accomplished, as is shown in Figure 25, by utilizing a pair of extra length block units 15 with their beveled portions at their outer corners and interposing between the same a pair of single rectangular block units 3 of 45 the type illustrated in Figures 13 and 19.

The general method of constructing a building is shown in Figure 7 wherein the foundation board 21 shown in Figure 8 is first set down and building units 1 are then positioned about the 50 margins thereof, the interlocking rods 22 being engaged through the aligned apertures in the several building units. At intervals at approximately the height of the various stories of the building, an elongated horizontal strip 23, such as is 55 shown in Figure 26, is laid over the several building units so as to firmly tie the elements of the structure together over an extended area.

The interlocking bars comprise cylindrical rods 60 preferably made of wood, or other suitable material, to snugly engage the apertures in the foundation board and the various building units. Such interlocking rods are made of various lengths so that two units may be united by a short bar or a long bar may be utilized which will extend to 65 substantially the height of the building which it is desired to erect, and all the units may be engaged over bars of such full length extent. Where a gable roof is to be applied, it is desirable to utilize rods of different lengths so as to conform 70 to the angle of the roof outline when the units are assembled. Likewise, when chimneys are to be erected, the rods selected for such construction should preferably be of substantially the full length of the chimney, as this secures a stronger

construction than where a plurality of shorter interlocking bars are used.

In addition to the standard building units to form the body portion of the structure, special units such as porch posts 24 and floor platforms 25, may be provided. Special units 26 for roof structures for the porches may also be provided. 5

It is planned to show on the foundation board by means of indicia such as dots, dashes, or crosses, given a distinctive number, the outline 10 of a building 25 corresponding, for example, to the type shown in Figures 1 and 2, and also other outlines suitably and distinctively numbered, showing the floor plan 26 of a building to correspond with the structure shown in Figures 3 15 and 4, and a floor plan 27 to correspond with the structure shown in Figures 5 and 6, respectively. Thus, the person using the miniature building units can erect with little difficulty a building corresponding to any of the three forms illustrated, 20 as well as many other types which can be provided for, and by following the outlines on the foundation board can erect a building with very little difficulty.

The structures, besides the variously shaped 25 building units, include window structures, such as are shown in Figures 9 and 10, which comprise apertured sheet metal members 31, 32, bent at their upper and lower ends so as to provide interlocking sections 33, 34 for engagement between 30 adjacent horizontal rows of building units. Likewise, a sheet metal door member 35 is provided, as shown in Figure 11, which has horizontally extending members 36, 37, at the top and bottom of the same to hold such member in position. 35

The roof structures are preferably in the form of folded members 41, 42 notched to provide for the chimney structures or such hip roofs 43 or gables 44, as may be associated with the main roof. Likewise, special roofs 45, 46 may be provided for the bay windows and porches of the structure. These roofs for the bay windows and porches, if desired, may have tabs or extensions to engage between the adjacent horizontal rows of building units, but ordinarily will remain in 45 position when set in place. Likewise, the upper roofs will ordinarily maintain themselves in position, particularly where they are notched for chimneys or for adjacent roof sections.

The method of proceeding to erect a structure with the units above described may be varied to a certain extent, but in general it is intended that the person desiring to erect one of the structures should select a front and side elevation of a structure that conforms to the building he proposes to erect and thereupon inserts in the holes of the plan marked to correspond with such building, such as plan 25 marked on the foundation board comprising the outline of the building shown in Figures 1 and 2, and sets into such holes along the line 25 shown on the foundation board a series of interlocking rods 22. He thereupon slides over such rods the lower row 10 of building units about the margins of the foundation board, and upon completing the bottom layer, proceeds to slide over the rods the second layer 20 of units, which, as shown in Figure 7, are staggered with relation to the first layer of units. He then, upon completion of the second row of units, decides upon the position for the windows and lays the third series 30 of units with spacing provided for the window areas into which he slides a sheet metal window member 31 intermediate the units. Where such window area is provided, the interlocking bars beneath the window must be of two- 70 75 80 85 90 95

block height and a new series of bars provided for the structure above such frame. The same is true with reference to any door frames. Where there are no windows or doors, the height of the 5 interlocking bars may be the full height of the structure, although a satisfactory structure can be built by using short lengths of interlocking bars in adjacent horizontal units.

At intervals at the height of the respective 10 stories, and shown in Figure 7 as just above the fourth row 40 of block units, a horizontal strip 23 is engaged with the interlocking bars and this serves to aline the interlocking bars and hold the structure against weaving or local displacement 15 of the units. The second story is laid in the same manner as the first story by selecting units of the desired character and where alcoves or corner structures are to be provided, they are set together in the manner shown in Figures 24 20 and 25 of the drawings.

As the building approaches the upper section where the roof is to be applied, it is necessary to use units of the type shown in Figures 14 and 20, having beveled portions so as to provide a suitable 25 angle for the roof to fit over and the interlocking bars must be selected of such length as not to interfere with the position of the roof. After the side walls and chimney of the structure have been 30 completely erected, a suitable roof section is selected and is fitted into position. Likewise, roofs for the porches and bay windows must be provided.

When the structure is completed, it will be 35 found that it has considerable stability and is able to withstand handling to a degree not possible with building blocks of ordinary type or of such structures which are interengaged in some other manner.

Other modes of applying the principle of my invention may be employed instead of those explained, change being made as regards the structures herein disclosed, provided the means stated by any of the following claims or the equivalent 5 of such stated means be employed.

I therefore particularly point out and distinctly claim as my invention:

1. A structure of the character described, having in combination a foundation board providing 10 a series of apertures, a series of interlocking bars adapted to be engaged in said apertures, apertured building units to engage over adjacent interlocking bars and cooperating with adjacent units to form a miniature building, and sheet 15 metal members having top and bottom horizontal flanges adapted to be engaged with said building units over open spaces in said building to provide a support for overlying units and said sheet metal members having openings into the interior 20 of the building to simulate doors and windows.

2. A structure of the character described, having in combination a foundation board providing 25 a series of apertures, a series of interlocking bars adapted to be engaged in said apertures, apertured building units to engage over adjacent interlocking bars and cooperating with adjacent units to form a miniature building, and units of greater length than such regular building units to be positioned angularly in the structure over longitudinal areas equal to the area of a single regular unit and to cooperate with such single regular units to 30 form structures having projecting portions outside of the rectangular plan areas.

35

WILLIAM KUPPER.
